CLAIM

The ornamental design for a vehicle body, as shown and described.

DESCRIPTION

FIG. 1 is a left front view of a vehicle body showing the new design;

FIG. 2 is a left side view thereof, the right side being a mirror image; and,

FIG. 3 is a left rear view thereof.

The broken line showing of tires, wheels, emblems, grille and windshield wipers is included for the purpose of illustrating non-claimed subject matter and forms no part of the claimed design.
